LINK CHAIN FOR A BRACELET OR SIMILAR ARTICLE

Mark Shofel, New York, N. Y.

Application April 10, 1957, Serial No. 45,673

Term of patent 3½ years

(Cl. D45—4)

Fig. 1

Figure 1 is an elevational view of a link chain for a bracelet or similar article showing my new design.

The back of the article is of substantially the same appearance as the front thereof.

I claim:

The ornamental design for a link chain for a bracelet or similar article, as shown and described.
